ABSTRACT: The hot box detector structure comprises a main enclosure and an upper deck enclosure. The main enclosure houses the radiometer which should be maintained at ambient temperature. For this reason, the upper deck enclosure is separated from the main enclosure by a suitable air space. It also supports a surrounding sun shade to further protect the main enclosure of the structure from the direct rays of the sun and thus prevent the building up of its internal temperature above the ambient. The tower enclosure rises from one end of the main enclosure and includes a window at its top or head through which the radiometer can view the passing hot elements of a moving train. The head of such tower also includes certain operative parts such as a shutter for the window, heating elements, shutter control, window washer and dryer, and the like. This head of the tower is heat insulated from the tower supporting structure and from the main enclosure.

BRIEF DESCRIPTION OF DRAWINGS

HOT BOX DETECTOR STRUCTURES FOR RAILWAYS

BACKGROUND OF INVENTION

The present invention relates to an improved hot box detector structure for detecting hot elements on railway vehicles, and in particular relates to a structure for the detection of overheated journals on railway cars.

The prior art shows various systems for detecting overheated journals on railway cars such as the scanning of those areas most nearly representative of the journal temperature. Such areas include the journal boxes, the axles, the wheel hubs, and other related parts. In providing such systems, it has been found desirable to maintain the basic detection apparatus at ambient temperature so that those changes in temperature of the passing train elements can be most accurately measured dependent upon their rise in temperature above ambient.

Thus, one of the objects of the present invention is to provide a structure for housing the radiometer which inherently maintains its internal temperature at ambient temperature regardless of hot sunshine or extreme cold.

The present invention accomplishes the above object by providing a main enclosure for the radiometer detection apparatus which has supported above it a so-called deck enclosure which includes a surrounding sun shade for protecting the main enclosure from the direct heat of the sun. Such deck enclosure is supported above the main enclosure with an intervening air space by a tower rising from the main enclosure at one end and by an interconnecting conduit member at the other end.

The upper deck enclosure is also employed for housing that portion of the system which involves heat producing parts and other operating means. Such artificial heat is maintained away from the main enclosure by heat insulating structural material located between them.

Since the upper deck portion also includes a window through which the radiometer can detect or view passing hot train elements, and since the window is tipped only slightly off the horizontal, such window is supplied with means for preventing the deposit of debris thereon. Such means includes a mechanical shutter, a window washer and a dryer together with means for intermittently operating the dryer for blowing dust away from the window during the passage of a train.

SUMMARY OF THE INVENTION

The invention in brief comprises a structure with a main enclosure for containing a radiometer. A deck enclosure is mounted over said main enclosure with an intervening air space except adjacent a connecting tower at one end of the main enclosure which includes a window through which the radiometer can view passing hot train elements.

Also the deck enclosure includes a sun shade substantially surrounding it for preventing the sun's rays from directly hitting the main enclosure.

Also, a normally closed mechanical shutter is located above the window, which shutter is capable of being actuated to an open position. The shutter is reflective on its lower surface for reflecting a test target into the radiometer which provides a viewing path substantially the same length as the path provided for viewing passing hot train elements. Such test path also includes the window with its then existing degree of transparency.

The above mentioned window for the structure allows the radiometer to view passing hot elements on a train, which has a nozzle connected through a control valve to a source of compressed air. There is means rendered effective by a passing train for intermittently acting on the control valve for releasing blasts of air across the face of the window.

Other objects, purposes, and characteristic features of this invention will be in part obvious from the accompanying drawings and in part pointed out as the description of the invention progresses. In describing the invention, reference will be made to the accompanying drawings.

FIG. 1 is a top view of the structure showing the upper deck and its surrounding sun shield as well as the top of the tower;

FIG. 2 is a side view of the structure with certain parts removed to show the general arrangement of the apparatus inside;

FIG. 3 is an end view to show the location of the sun shield and the manner in which the deck enclosure overhangs the lower main enclosure of the structure;

FIG. 4 is a top view of the tower showing the shutter with the cover plate removed and also indicating the location of the window heater elements; and

FIG. 5 shows the control system for the shutter and its related window washer and dryer.

DESCRIPTION OF THE PREFERRED EMBODIMENT

The following detailed description is made in coordination with the drawings and such description includes both structural and functional details of the present embodiment. The drawings have been made by using conventional illustrations and symbols to simplify the disclosure, but it is intended that these conventional illustrations be used for an understanding of the invention rather than showing all of the structural details.

The hot box detector structure comprises a main enclosure 5 as shown in FIGS. 2 and 3. This structure has a tower 6 at one end which rises substantially upward terminating in a head 7. A deck enclosure 8 is fastened to the tower 6 and head 7 at one end and is fastened to the main enclosure 5 at its other end by a conduit 9. This leaves a substantial space between the main enclosure 5 and the deck enclosure 8 as can best be seen in FIG. 2.

The main enclosure 5 contains a radiometer 10 which is connected by suitable cables to the terminal board 11 in the deck enclosure 8, and from such terminal board 11 suitable cables pass through the conduit 12 to control housings or other apparatus for advising wayside personnel and others of the degree of heat above ambient of the hot elements viewed on a passing train. The main enclosure 5 has a mirror 14 which reflects what is viewed either on the passing train or the test target 15. The underside of the mechanical shutter 16 (see FIG. 5) is preferably a polished surface, such as a nickel plate surface. Such surface reflects the temperature of the test target 15 which is held at an appropriate temperature above ambient by the target control apparatus 17 so that the radiometer will be set for giving a corresponding signal when the temperature of the hot train elements is similarly above ambient temperature.

As those skilled in the art well know, actual empirical data has proven that over a wide range of ambient temperatures, the temperature differential indicative of bearing failure varies over a substantial range. However, the test target 15 can be set for a temperature above ambient which is usually indicative of incipient journal bearing failure. For example, when the radiometer is set to view wheel hubs, a temperature level of 60° F. above ambient is found to be the threshold level commensurate with potential journal bearing failure. This level can be easily changed to higher or lower levels if experience indicates such a change is desirable. The desired temperature level is established by energizing the small heater coil of the test target 15 from a suitable source controlled dependent upon both ambient and target temperature.

The radiometer 10 and the test target 15 and the related apparatus is preferably employed in a system such as shown in the prior application Ser. No. 732,453 to Sibley and Pettitt filed May 27, 1968. In this prior application, the test target 3 is on the back of the movable mechanical outside shutter 1; but in the present case, the test target 15 is stationary and is reflected by the mirror like surface on the lower side of the mechanical shutter 16. This location of the reflecting surface and test target 15 includes in its path the window 18 (see FIG. 5). If the window has become dirtied, its transparency may be reduced and such reduction in transparency is effective for

both the test and regular operations. In this connection, reference to FIG. 2 shows the general path for the optical arrangement, and such test path is substantially the same length as the actual path to the hot elements on a train when viewed with the shutter 16 open.

The window 18 is preferably of a suitable glass so as to pass the wave lengths of heat here involved. One such glass can be quartz. Whether or not such window is transparent or translucent with regard to visual light rays is immaterial so long as such window is transparent to the wave lengths of temperatures here involved. The system shown in the prior application Ser. No. 732,453 takes steps or counts to adjust the apparatus to values which render the apparatus the most accurate with regard to detecting the temperature of the hot elements on the passing trains. The target control 17 for example may also include a thermostat on the outside of the main enclosure 5.

The upper deck enclosure 8 is shown in FIG. 1 as having sun shades 19 on either side. These shades 19 extend outwardly with an air space between them and the deck enclosure 8 also between them and the main enclosure 5 as can be seen in FIG. 3. In lieu of the shades 19 extending outwardly to the left and joining in FIGS. 1 and 2, the entire deck enclosure 8 including the sun shades 19 extend out sufficiently to protect the main enclosure 5 from the sun's rays coming from that direction. If desired, these shades 19 can be extended around the right hand end seen in FIG. 2; but, in practice the detector structure is mounted low between the ties and close to the rails so that such right hand extension could not be used. However, there may be some instances where such right-hand extension would be desirable.

The head 7 of the tower is elongated over the tower 6 as seen in FIG. 3 and includes in its mechanical connection to the tower itself, heat insulation material 20 which retards the direct conduction of heat to the main enclosure 5.

Above the heat insulating material 20 is a plate 21 best shown in FIG. 5 which includes the window 18, and mounts the operating mechanism 22 for the shutter 16 as well as including an insert for the nozzle 23 of the window washer and dryer. The plate 21 has attached thereto on its lower side heater members such as 24 and 25 of FIGS. 4 and 5. This plate 21 is also shown in FIG. 4 looking from the top. The shutter 16 is shown in its open position, but it is also movable over the window 18 as shown in dotted line. The shutter 16 not only covers the window 18 but it assumes an appropriate position beneath the opening in the top plate 26 as best seen in FIG. 1. In this way, all of the edges of the shutter are protected except the lower edge. Such protection is to minimize tampering by unauthorized personnel.

This upper plate 26 is spaced slightly from the shutter and itself provides some dissipation of the direct heat from the sun. The plate 26 in cooperation with the shutter 16 thus prevents the direct shining of the sun on the plate 21.

Any heat that collects in the main enclosure 5 will readily rise to the tower structure. Any heat that is generated by the heater elements 24 and 25 will be substantially maintained in the tower structure.

It is noted that the thermostat 30 for the heaters 24 and 25 is located in a generally open area so as to be unaffected by the detector structure itself and will be effective to render such heaters active only when ambient temperatures approach freezing temperatures. The thermostat 31 located on the back of plate 21 is set to open the energizing circuit for the heaters 24 and 25 at some suitable higher temperature. For example, thermostat 30 could be set to close at 35° F., and thermostat 31 could be set to open at 45° F.

The heaters will then supply heat to the plate 21 and indirectly to the window 18, the shutter 16 and top plate 26. When this temperature builds up to approximately 45° F., the circuit will be opened by the high thermostat 31 which is mounted on the back of the plate 21. In other words, so long as there are freezing temperatures outside, the heat will be at least intermittently applied to the plate 21 so as to maintain it at approximately 35° F.

If there is no convenient point to mount the thermostat 30, it can be removed. In such case, the thermostat 31 would be adjusted so as to have a wide overlap in its operation. For example, its contacts could be adjusted to close at 35° F. and to remain closed until the temperature of the plate had been raised to 45° F.

The operating mechanism 22 for the shutter 16 is a small compressed air cylinder which when it receives air pressure will move the shutter 16 to its open position shown in FIG. 4, but when such air pressure is removed, then there are suitable springs within the mechanism which will return the shutter to the closed position illustrated in FIGS. 1 and 4.

A suitable source of compressed air is located adjacent the wayside of the railroad, such as the compressed air tank 34. This tank 34 is supplied with compressed air from the compressor 35 with an automatic pressure control connection. The compressor 35 is, of course, operated from a suitable electric source. The automatic valve 36 allows the passage of air in the direction indicated by the arrow, but when the top pressure of the tank 34 is reached, the compressor 35 stops and this one-way valve 36 prevents any back flow of air pressure. This pressure is supplied through a normally closed electric valve 37 to the operator mechanism 22. This valve 37 is opened only upon the supply of positive energy as will be shortly discussed.

Associated with the compressed air source is a liquid tank 38 which is filled periodically by suitable maintenance personnel. When the tank is being filled, the manual-automatic valve 39 is manually closed. When this filling operation is completed and the liquid tank tightly capped, the manual valve 39 is opened and it becomes an automatic one-way valve so that the compressed air from tank 34 flows into the liquid tank and supplied liquid to the normally closed electric valve 40.

The liquid or fluid used in tank 38 can be any suitable window washing fluid. Basically it is water with a detergent and with an antifreeze such as alcohol for cold climates. Also, a suitable amount of wetting agent can be used.

A group of relays WDP, SC, SP, SPP and TR are shown associated with the valves 37, 40 and 41. The relay WDP repeats the wheel detector so as to be actuated each time a wheel is detected. Such wheel detector also triggers the apparatus used for the detection of the temperature of the associated journal bearing. The control for the apparatus associated with the radiometer is fully described in the above application Ser. No. 732,453.

Each time the wheel detector repeater WDP picks up, it supplies energy through front contact 42 to relay SC. This relay SC is sufficiently slow releasing so as to be maintained in a picked up position so long as the train continues to move at least above some practical low value of speed. When this relay SC is picked up, it closes front contact 43 and energizes valve 37 which allows the compressed air to operate the mechanism 22 to open the shutter.

Following the picking up of relay SC, front contact 44 energizes relay SP which in turn closes front contact 45 to energize relay SPP. When these relays have all picked up, front contact 46 of relay SC supplies energy through the winding of relay TR, back contact 47, front contact 48, to the control valve 41. Thus, each time energy is supplied to the relay TR, the control valve is energized and allows the flow of compressed air through the nozzle 23. Since this relay TR opens its back contact 47 upon picking up, it releases the control valve 41 and shuts the air off. But in due course, the relay TP releases and again closes contact 47. This repeating operation continues so long as a train is continuously detected as passing over the associated wheel detector.

When the train leaves, i.e., ceases to actuate the wheel detector, the relays WDP, SC, SP and SPP drop away in succession. When the relay SC releases and closes back contact 46, energy is supplied through front contact 49 of relay SP and front contact 50 of relay SPP to energize the control valve 40 during the time that relay SP is releasing. In other words, the flow of fluid from the tank 38 is of limited duration. The

release of front contact 49 of relay SP supplies energy through front contact 48 of relay SPP to control valve 41 and allows the compressed air to flow until the relay SPP releases.

During this operation, the shutter 16 is closed since the release of relay SC opens front contact 43 which removes energy from the control valve 37. In other words, the shutter being closed, any dirt that is present on the reflecting surface of the shutter or on the face of the window 18 can be washed away in a single operation followed by a blast of compressed air for drying them off. The closure of the shutter then places the apparatus in condition for the testing of the target temperature as described in the prior application Ser. No. 732,453.

Returning to the housing features, it will be noted that the cables which enter the deck enclosure 8 through conduit 9 are sealed in their positions by suitable caulking material so as to fully close any air spaces leading to the main enclosure 5. Also, the pipes leading from tanks 34 and 38 enter the deck enclosure 8 and feed through a suitable aperture in the wall of the tower. The wires from the relays are fed through conduit 12 to the terminal board 11 and then to the control valves 37, 40 and 41 through an opening in the wall of the tower. These openings into the tower 6 are also caulked to prevent any air spaces between the tower 6 and the deck enclosure 8. In other words, all connections and tests in the field can be made at the terminal board 11. The main enclosure 5 and tower 6 remain closed and substantially sealed from the outside.

In brief, the present invention resides in a structure for housing the radiometer which will maintain itself substantially at ambient temperature and in so doing also provides an operating structure which is easily maintained for viewing the hot elements of a passing train to determine whether or not they are dangerously hot, i.e., at a temperature which might precipitate possible accidents.

While there has been described what is at present considered to be the preferred embodiments of the invention, it will be obvious to those skilled in the art that various changes and modifications may be made therein, without departing from the invention.

What I claim is:

1. A hot box detector structure comprising, a main enclosure containing a radiometer, a tower connected to said main enclosure by a heat insulating material, said tower having a window at its upper end through which said radiometer can view and provide a responsive output to passing hot elements, an electric heater element disposed in the upper part of said tower operative when energized for heating said window and preventing frosting of the window, whereby the main enclosure is substantially unaffected by the heating of the window due to the presence of the insulating body.

2. The structure as specified in claim 1 including a dock enclosure mounted over said main enclosure with an intervening air space, overhanging said main enclosure, and a sun shield substantially surrounding said deck enclosure.

3. A structure as specified in claim 1 wherein a normally closed mechanical shutter is located above said window capable of being actuated to an open position, said shutter being reflective on its lower surface, and wherein said radiometer is provided with a test target so located as to be reflected by said lower surface of said shutter into said radiometer and having a viewing path substantially the same length as the path provided for viewing passing hot train elements, whereby said test path also includes said window with its then existing degree of transparency.

4. A hot box detector structure comprising: a main enclo-

sure for containing a radiometer, a tower insulatively connected at its lower end to said main enclosure and having a window at its upper end through which said radiometer can view passing of hot elements, a shutter above said window capable of being operated to an open position, an electric heater element substantially surrounding said window in the upper part of said tower, and thermostatic control for said heater element to maintain a temperature above freezing whereby said shutter and said window are prevented from becoming frosted and accumulating snow, and said tower and main enclosure are isolated by said insulative attachment for preventing the heater from affecting the operability of the radiometer.

5. A structure as specified in claim 4 wherein a cover plate is mounted over said shutter but allowing free movement thereof, said cover plate also having an opening substantially opposite said window.

6. A structure as specified in claim 4 wherein a shroud is mounted over said shutter but without materially obscuring said window and permitting the free movement of said shutter.

7. A hot box detector structure as specified in claim 1 wherein means is provided for spraying said window with fluid, and wherein additional means is provided for flowing air across said window for a limited time following said spraying action.

8. A structure as specified in claim 7 wherein said window spraying means is effective upon a departure of a train but before said shutter is closed.

9. A structure as specified in claim 8 wherein said air blowing means stops blowing air concurrent with the closure of said shutter.

10. A hot box detector structure including a window through which a radiometer can view passing hot train elements comprising, a source of compressed air, means for connecting said source of air to a nozzle adjacent said window through a normally closed control valve, means rendered effective upon the passage of a train for intermittently actuating said valve to release blasts of air across the face of said window, a source of fluid under pressure located adjacent said detector structure, means connecting said source of fluid to a nozzle adjacent said window through a normally closed control valve, and means rendered effective upon the passage of a train out of the section adjacent said detector structure for momentarily actuating said fluid control valve for releasing a limited quantity of fluid just prior to the last blast of air across said window.

11. A hot box detector structure including a window through which a radiometer can view passing hot train elements comprising, a source of compressed air located adjacent to said hot box detector structure, means for connecting said source of air through a nozzle adjacent said window and also through a normally closed control valve, and means rendered effective upon the passage of a train for actuating said control valve to release a blast of air across the face of said window, a source of fluid under pressure located adjacent said structure, means connecting said source of fluid to a nozzle adjacent said window through a normally closed control valve, means rendered effective upon the departure of said train for temporarily actuating said fluid control valve for releasing a limited quantity of fluid from said nozzle, said means also causing actuation of said air control valve for effecting a final blast of air across said window, and heater means located adjacent said window for maintaining the temperature thereof at a value above freezing.
